Primary Examiner — Robert M. Spear*Assistant Examiner* — Darcey E Heflin(74) Attorney, Agent, or Firm — Breiner & Breiner, L.L.C.(57) CLAIM

The ornamental design for a cap for container, as shown and described.

DESCRIPTION

FIG. 1 is a perspective view of a cap for container showing my design;

FIG. 2 is a side elevational view of my design;

FIG. 3 is a top view of my design; and,

FIG. 4 is a bottom view of my design.

The broken lines in the figures represent portions of the cap for container that form no part of the claimed design.
